UNITED STATES PATENT OFFICE.

HENRY E. HYATT, OF SINGER, LOUISIANA.

WATCH PENDANT.

Application filed July 29, 1925. Serial No. 46,849.

This invention aims to provide a dust-proof pendant for a watch, and so to construct the device that an accidental setting of the watch will be avoided. Other objects 5 will be made manifest as the description proceeds.

It is within the province of the disclosure to improve generally and to enhance the utility of devices of that type to which the 10 invention appertains.

With the above and other objects in view which will appear as the description proceeds, the invention resides in the combination and arrangement of parts and in the 15 details of construction hereinafter described and claimed, it being understood that changes in the precise embodiment of the invention herein disclosed, may be made within the scope of what is claimed without departing from the spirit of the invention.

In the drawings:—

Figure 1 shows in section, a device constructed in accordance with the invention, parts being in elevation; Figure 2 is a top plan; Figure 3 is a plan showing a screw driver which may be used in connection with the device shown in Figures 1, 2 and 4; Figure 4 is a sectional elevation showing a slight modification.

30 The numeral 1 marks a watch having a pendant 2. A stem 3 is journaled in the pendant 2 and has a transverse shoulder 4 located within the pendant 2, the shoulder being adapted to cooperate with a flange 5 on the outer end of the pendant. The stem 3 is threaded at 6 into the bore 7 of a crown 8 having a recess 9 receiving the outer end of the pendant 2. A compressible washer 10, made of leather or any other suitable 40 material, is seated in the recess 9 of the crown 8 and bears on the outer end of the pendant 2. The stem 3 extends through the washer 10. A bow 11 is connected at 12 to the pendant 2 for swinging movement in a well known way. The bow 11 has an inwardly extended projection 14 which is prolonged almost into engagement with the crown 8. A retainer 15, such as a screw, is threaded into the bow 11 and the projection 45 14 and enters the bore 7 or the crown 8, the screw 15 being provided at its inner end with a concaved seat 16 adapted to receive the rounded end 17 of the stem 3. The screw 15 has a longitudinal slot 19 extended 50 inwardly from the outer end of the screw, and extended entirely through the screw, 55

from side to side. Into the outer end of the slot 19 may be inserted a screw driver 20, which may be used as a watch charm.

In Figure 4 of the drawings, parts hereinbefore described have been designated by numerals previously used with the suffix "a". The modification consists in forming an outward projection 21 on the bow 11^a and mounting a cap 22 removably on the projection 21, the cap 22 housing the end of the screw 15^a.

The device requires no adjustment whatever for winding, since the crown 8 can rotate on the inner end of the screw 15, that portion of the screw which extends into the bore 7 of the crown being smooth. In order to set the watch, the screw 15 is backed out a little, and the bow 11 is swung over to one side. Then, the stem 3 may be pulled outwardly into setting position, by means of the crown 8, the shoulder 4 on the stem 3 engaging the flange 5 of the pendant 2. The bow 11 is yieldable enough so that when the screw 15 is advanced into engagement with the stem 3, as shown in Figure 1, the stem and the crown 8 will be carried inwardly, thereby compressing the washer 10, so that the washer will be thoroughly effective to exclude dust. As a matter of fact, not merely a dust-proof joint, but a water-proof joint is formed. The setting of the watch cannot be changed accidentally by hand, because the screw 15 holds down the stem 3. The rotary bearing between the screw 15 and the stem 3 can be oiled by the user of the watch, it being unnecessary to do any watchmakers work in order to effect such an oiling. The article calls for no adjustment of parts, so far as the winding of the watch is concerned, since the winding may be brought about, as hereinbefore explained, when the device is arranged as shown in Figure 1. The stem 3 may be adjusted longitudinally by substituting for one washer, another washer of a different thickness. The ends of the bow 11 will not wear loose readily, because the bow does not have much swinging movement, it being necessary to swing the bow only when the watch is to be set.

The slot 19 in the screw 15 has two purposes: first, it may be used in threading the screw 15 in or out; secondly, the slot may be opened slightly, when the screw is detached, thereby spreading the screw and causing the screw to take up wear, when it is again threaded into place.

What is claimed is:—

1. In a watch comprising a pendant, a stem in the pendant, a crown carrying the stem, a washer in the crown and cooperating with the end of the pendant, and a bow mounted for swinging movement; an improvement which consists of a combined means for holding the bow against swinging movement, for holding the stem against accidental setting movement, and for compressing the washer, said means embodying a member held in the bow for adjustment at the will of an operator and entering the crown and engaging the stem.
2. A device of the class described, constructed as set forth in claim 1, and further characterized by the fact that said member is

accessible through the outermost portion of the bow for adjustment at the will of an operator.

3. A device of the class described, constructed as set forth in claim 1, and further characterized by the fact that said member is in the form of a screw, threaded into the outermost portion of the bow and having a screw-driver slot accessible through said portion of the bow and deep enough, measured longitudinally of the screw, to permit an expansion of the screw to take up wear therein.

In testimony that I claim the foregoing as my own, I have hereto affixed my signature.

HENRY E. HYATT.
